United States Patent Office.

NICHOLAS S. VEDDER, OF TROY, NEW YORK.

Design No. 2,736, dated August 6, 1867.

DESIGN FOR A PLATE AND DOORS OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Design for Plates of a Stove, of which the following is a full and exact description, reference being had to the accompanying photographs, in which—

Figure 1 represents a front oven-plate.

Figure 2, a large door, and

Figure 3 a small door of a stove.

The design for the front oven-plate consists of four sceptre-like ornaments, *r*, on four oblong, round-top, plane-surface panels, *s*, formed by ornamented mouldings, *t*, on the plane surface of that plate, all shaped and arranged so as to appear as represented in fig. 1. The design for the large door consists of the ornamented shield *u*, and surrounding ornamental moulding *v*, on the plane surface *w*, and angle ornaments *y y y y*, on the corners of the border moulding, all formed and arranged as shown in fig. 2. And the design for the small door-plate consists of the compound ornament *x*, and moulding *z*, on the plane-surface panel, and the angle ornaments *y' y' y' y'* on the corners of the border moulding, all shaped and disposed so as to appear as represented in fig. 3.

What I claim as my invention or production, and desire to secure by Letters Patent, is—

The design for plates of a stove herein set forth and shown.

NICHOLAS S. VEDDER.
